PRINTING TELEGRAPH SYSTEM

Edmond Maurice Deloraine, New York, N. Y., assignor to International Standard Electric Corporation, New York, N. Y., a corporation of Delaware

Application October 18, 1941, Serial No. 415,554

29 Claims. (Cl. 178—84)

This invention relates to printing telegraph systems and, more particularly, to a printing telegraph for radio use.

An object of the invention is the provision of a rugged equipment, light in weight, for portable use, especially adapted for communication with aeroplanes.

Another object of the invention is the provision of a printer system, wherein the signals are of a kind which will practically insure privacy of the matter transmitted.

Another object of the invention is the provision of a transmitter of novel design, by which signals of the start-stop type may be transmitted by a smoothly operating mechanism in which jars and noise are eliminated.

Another object of the invention has been to limit the number of mechanical movements of the apparatus to vary few, these to be of such a nature as to render the amount of mechanical maintenance on the equipment almost negligible.

Still another object of the invention is the provision of a printing telegraph system designed so as to insure that letters or figures printed by the receiver cannot be wrong, so that if used for radio communication excessive noise or other disturbances would render the letters or figures illegible, but in no case can one character be replaced by another.

A further object of the invention is to provide a facsimile telegraph system designed to avoid the vertical displacement of the letters on the tape when there is an appreciable difference in speed between the transmitter and the receiver, such speed difference in the present invention resulting only in the slanting slightly forward or backward of the characters, the direction and degree of slant serving as a guide to indicate the direction and extent of adjustment required by the printer motor governor.

In conventional start-stop transmitters it is customary to stop a rotary member, once each revolution, by the disengaging of a clutch, controlled electrically or mechanically, and to start the member by engaging the clutch at the beginning of each letter. With such an arrangement the rotary member must be of light weight, for otherwise there would be too great a strain on the clutch due to the inertia of the rotary member. Furthermore, such clutch controlled devices are noisy in operation, and for some purposes, noise is objectionable.

The transmitter, as disclosed in a preferred embodiment, has a smooth, quiet, cam operated mechanism of the "sewing machine" type. A

drum, perforated about its circumference in a series of rows, is driven uninterruptedly at a uniform rate by a motor. A key operated shutter is provided for each row of perforations, the perforations of each row being arranged according to the elements forming a character in a code.

The invention will now be described in detail with the aid of the accompanying drawings.

Referring now to the drawings:

Figure 1 is a side view, partly in section, of a transmitter;

Figure 2 is a section taken through the transmitter near the right hand side thereof;

Figure 3 is a plan view taken from the right hand portion of the top of the transmitter, showing the location of various shafts;

Figures 4 to 7 and 9 shows details of the mechanism;

Figure 8 shows a part of the perforated surface of the drum;

Figure 10 is a front view of the transmitter, partly in section and somewhat enlarged;

Figure 11 shows diagrammatically a transmitter circuit;

Figure 12 is a schematic showing of the printer mechanism and the printer circuits;

Figure 13 is a top view of the printer chariot;

Figure 14 is a drawing of a transmitter circuit; and

Figure 15 shows diagrammatically the arrangement by which received impulses are formed into built-up characters.

The transmitter mechanism is supported in a framework consisting of a base 10, uprights such as 11 and 12, and a top plate 13. Drum 14, provided with suitable bearings at each end, turns on rounded end sections of a stationary shaft 15 supported by blocks 16 (Fig. 3) at each end secured to the base. A motor 17 (Fig. 2) having suitable speed governing means drives drum 14 through step down gear 18 meshed with gear 19 which is part of the drum assembly. Mounted on the drum assembly, adjacent to gear 19, are cam wheels having cams 20 and 21 formed thereon. The shape of the cams and their relative positions is shown in Fig. 2.

A roller 25 mounted in rocker 26 adjustably secured to arm 27 by screws 28 is held by spring 29 (Figs. 2, 3 and 5) against the surface of the wheel of cam 20. Arm 27 has a top portion which is secured to bail 30 that extends across the top of the transmitter and is free to turn on shaft 35, which likewise extends across the top of the transmitter and support both arms of bail 30, only one of which is shown in the drawings.

Since arm 27 and ball 30 are secured to each other, it will be understood that as cam 20 turns ball 30 will be stationary when roller 25 is over the low portion of the wheel, as shown in Fig. 1, for about three quarters of a revolution of the drum, and upon engagement of cam 20 with roller 25, arm 27 will be turned on shaft 35 and ball 30 lifted until the cam moves from under the roller.

A second ball 36, similar to ball 30 but having longer arms, is secured to shaft 35. Ball 36 tends to move with ball 30 being connected thereto by spring 37 disposed on shaft 35 (Fig. 3) and having one end over a stud 38 in ball 30, and the opposite end under a similar stud 39 in ball 36 thus tending to hold the studs 38 and 39 in engagement with each other. The balls are for the purpose of regulating the operation of shutter members described further on.

Release lever 45 is secured to shaft 35 and cooperates with a hook shaped latch 46 (Fig. 2) operated from the keyboard to control the operation of ball 36. The mechanism for operating latch 46 will be described below.

Supported by the framework of the transmitter is a shaft 50 on which all of the key levers 53 are rotatably mounted. A key lever is shown in Figs. 1 and 9. Each key lever is provided with an upright arm 51 and a depending arm 52 which are guided in slots in combs 54 and 55, respectively. This arrangement is to prevent side twist of the key levers in their bearings on the shaft. Each key lever is associated with a member 56 (Fig. 6) having arms 57 and 58, said member being also pivoted on shaft 50. Member 56 is free to rotate in respect to the associated key lever within the limits of a pin and slot arrangement consisting of a capped pin 59 projecting from the key lever into a slot 60 in arm 58. A piano wire spring 61, attached to each member 56, tends to urge the member to turn in a counterclockwise direction, as viewed in Fig. 1. To each key is pivoted a pawl 62 on a pivot 63. The top part of the pawl has a turned over section 64 which engages the edge of arm 58 and normally rests on the upper edge of keybar 53. This limits the movement of the pawl by spring 65 in a counterclockwise direction. With this arrangement, when a key is depressed, pawl 62 tends to rotate member 56 in a clockwise direction, as viewed in Fig. 1, but if member 56 is restrained from moving by means shortly to be described, pawl 62 is held by arm 58 and the movement of the key turns the pawl on its pivot and spring 65 is stretched and continues to exert pressure on arm 58 of member 56, through the turned over part 64 of the pawl, sufficiently great as to cause a clockwise movement of the member against the tension of its spring 61 when the member is subsequently released. In order words the stressing of the spring 65 creates a bias which later is effective to cause operation of certain parts.

The vertical arm 57 of each member 56 has a rounded end which fits into a correspondingly shaped aperture in a shutter 70, one of which is provided for each key lever. The shutters are free to reciprocate in guideways in blocks 71 and 72. The ends 73 of the shutters are further guided by slots cut in guide block 74, and through the base of each slot is a hole 75 which extends through the top plate of the transmitter.

The shutters may be selectively withdrawn toward the right of the drawings by the respective keys and cooperating timing mechanism, now about to be described, uncovering one at a time, the apertures 75 leading to the surface of the

drum so that light from lamp 80, which shines through a diffusing medium 81, such as ground glass, can strike the slanting surface of an arcuate mirror 82 which reflects the light uniformly over the ends 73 of all shutters with substantially the same intensity, and in the event one of the shutters is withdrawn leaving the hole 75 uncovered, a ray of light can strike the surface of the drum and enter the perforations therein as it rotates, the light being modulated by the perforations in the drum which by their spacing serve as a light chopper.

The incoming light strikes mirror 83 and is reflected thereby to mirror 84, both mirrors being supported by a member 85 secured to stationary shaft 15. A photo-electric cell mounting 86 secured to shaft 15 holds photo-electric cell 87 which responds to rays of light reflected thereon from mirror 84. The circuits from the photo-electric cell are brought to the outside of the drum through opening 88 and longitudinal opening 89 in shaft 15, the latter opening extending through the shaft to the end thereof opposite that with which the driving mechanism is connected.

Timing and reset mechanism

Near each end of shaft 50 and rotatably supported thereon, is an irregularly shaped bar 90 (Fig. 2) only one of which is shown in the drawings. Between the longer, forward ends 91 of these bars is carried a ball 92 and the rear ends of the bars are connected by a hollow tube 93 to stiffen the ball supporting structure. Spring 94, between a stud on arm 91 and a support 95 secured to the frame, serves to hold the assembly in the position shown in the drawings.

A rod 96 (Figs. 2 and 7) has one end connected to a stud 97 on arm 91 and the other formed into a hook 98 engaging stud 99 at one corner of a triangular shaped member 100 pivoted near its opposite lower corner on a short shaft 101 rotatably supported in bearing block 102 (Fig. 3) on the top of the transmitter. A second member 103, similar in shape to 100, is pinned adjacent thereto to shaft 101. The two triangularly shaped members are yieldably connected to each other by spring 104 which engages stud 105 on member 100 and stud 106 on member 103, the spring normally holding the two studs together.

To the opposite end of shaft 101 is secured (Figs. 2 and 3) hook 46, which was referred to above. The hook is provided with a depending tip 107 which cooperates with a similar upwardly extending tip 108 on release lever 45, the arrangement being for the purpose of preventing premature release of lever 45 under certain conditions during the part of the cam cycle which tends to elevate the tip of the lever.

During each rotation of the transmitter drum, the parts occupy the position shown in Fig. 2, but once each cycle, cam 20 engages roller 25, thus rotating arm 27 in a counterclockwise direction and elevating ball 30 secured thereto on shaft 35 against the tension of spring 29 and also spring 37 in case the outer ball 36 is restrained from moving. Ball 36 secured to shaft 35 and spring connected to ball 30 normally is prevented from rotating, since shaft 35 is held against rotation by lever 45 which is under hook 46. A small degree of motion occurs between 45 and 46 providing sufficient clearance to permit hook 46 to be rotated free of lever 45 after a key has been operated, provided roller 25 is on the low part of the cam wheel.

When any key is depressed, the part 86 thereof

engages ball 32. An arrangement of balls 111 (Fig. 1) is provided in a suitable support 112 according to known practice, to prevent more than one key from being depressed at a time.

In every case the downward movement of any key depresses ball 32 and turns bar 30 secured thereto on shaft 58, pulling rod 96 downward and turning the triangular member 100 on shaft 101 and stretching spring 104. If the roller 25 is on the low part of the cam wheel, balls 30 and 36 are in their lowermost position and triangular piece 103 will be pulled in a clockwise direction by spring 104 which connects the two pieces together and this will turn shaft 101 and hook 46 secured thereto out of the path of 45 against the tension of spring 48, so that when roller 25 next rises up on cam 20, balls 30 and 36 will move upward together. This will release the shutter associated with the operated key and permit its movement to selected position.

If a key is depressed in the brief interval when cam 20 is passing under roller 25, ball 30 operates in the usual manner, but with this condition, lever 45 is pressed against hook 46 by spring 37 connecting the two balls, and the tip 107 of hook 46 is behind tip 108 of lever 45 holding the hook over the end of the lever, thus preventing the disengaging of these parts. In this case, due to the operation of a key, member 100 has been rotated on shaft 102, thus stretching spring 104. The parts are held in this position since the key is locked down by keyboard locking mechanism, which will be described below. As the cycle progresses and roller 25 is again on the low part of the cam wheel, tension tending to elevate ball 36 is removed lowering the end of lever 45, and since hook 46 is already under tension of spring 104 tending to turn it in clockwise direction immediately on the disengaging of 107 and 106, the end of the hook is moved out of the path of lever 45 against the pull of spring 48 so that on the next cam cycle, ball 36 will rise with ball 30, to permit the movement toward the right of the shutter member 70 attached to the operated key.

As already explained, when a key is depressed the tip of a pawl 62 carried thereby, engages the edge of arm 58 of the associated shutter operating member. Pawl spring 65 tends to rotate 58 against the tension of its spring 61 in a clockwise direction to withdraw shutter 70, and this tension is exerted on the shutter member as long as the key is depressed.

Each key 53 is provided with a depending member having a tooth 115 on the under side of which is formed a cam surface that engages with the turned over edge 116 of a locking bail 117. The latter is secured to one face of blocks 118, Fig. 2, rotatably mounted in suitable bearings on opposite sides of the keyboard. Spring 119 tends to rotate the bail in a clockwise direction, as viewed in Fig. 2. The arrangement is such that the tooth of a key when pressed engages the edge of the bail, rotates the latter in counter clockwise direction and when the tooth passes below the edge of the bail, the latter snaps over the upper edge of the tooth holding the key in its depressed condition.

The keys are released from the bail by means including an arm 121 oscillated by cam 21. The arm is operated immediately after cam 20 has passed under its roller 25.

Arm 121 is pivoted at 122 and carries a roller 120. Spring 123 holds the roller against the cam surface. The opposite end of the arm has a de-

pending projection 124 which strikes the end of an upright arm 125 after a key has been operated for the purpose of resetting the mechanism. Arm 125 is rotatably supported by shaft 128 (Figs. 2 and 10) carried between the ends 127 (Fig. 2) of two levers 128, only one of which is shown, rotatably mounted at opposite sides of the keyboard on shaft 129. Shaft 129 has a second pair of levers 130 pivoted thereon, adjacent to and outside of levers 128. Levers 128 and 130 are yieldably connected together by springs 131 (Fig. 10) disposed on shaft 129, the ends of the springs engaging respectively, studs 132 on levers 130, and studs 133 on levers 128. Between their front ends, levers 130 support a shaft 110 (Figs. 1 and 3).

A shaft 134 (Figs. 1 and 10) rotatably supported by end plates on opposite sides of the machine, carries two approximately vertical arms 135, extending upward on opposite sides of the shutter assembly, which support between them a bail 136 immediately in front of the ends of shutters 70. The bail is held in contact with the ends of the shutters by spring 137 on shaft 126 (Fig. 2) which tends to move arm 125 toward the left and hold the arm in engagement with a horizontal extension 138 integral with one of the arms 135. Figure 2 shows the normal unoperated positions of these parts with the end of arm 125 out of the path of the member 124 depending from the cam-controlled arm.

Each lever 130 carries an inwardly projecting cam surface 139 which cooperates with cam surfaces 140 secured near opposite ends of locking bail 117. When the assembly including arms 130 is turned on shaft 129 in a counterclockwise direction, as viewed in Figs. 1 and 2, which occurs in a reset operation, the cams engage and the locking bail is turned in a counterclockwise direction releasing whatever key has been depressed.

Spring 141 (Fig. 1) holds levers 128 and arms 130 in their normal unoperated positions.

Referring to Figs. 1 and 5, each shutter has a latch 145 pivoted in a circular hole 146 which is part of an irregularly shaped recess formed in the shutter. Spring 147 normally holds latch 145 against a projection 47 formed on the shutter. A nose 148 on the latch is disposed so as to be to the left of a depending edge 149 carried by bail 36 when the shutter is in unselected position. The spring and latch are retained in the recess by thin plates 41, spot welded to opposite sides of the respective shutters.

Bail 30 is provided with a similar depending edge 150. Upwardly extending projections 151 formed on the edges of the respective shutters cooperate with bail edge 150 to lock the shutters in selected position, as shown in Fig. 5, where the projection 151 of a selected shutter is shown to the right of bail edge 150 where it remains until the bail is elevated by the cam wheel 20.

It will be apparent that drum 14 may be perforated to transmit elements of a character in any desired kind of code. For example, each key might control the transmission of a start pulse followed by the character impulses of a well known start stop code, followed by the usual stop impulse. Perforations might be made for the transmission of start and stop impulses individual to each circumferential row of character perforations.

In one embodiment of a transmitter according to the present invention, a shutter member 155 (Fig. 1) may be provided which is somewhat different in structure to shutter 70, in that the

upper edge thereof is cut away so as to be clear of bails 30 and 36 and the end is provided with a hook 156 that engages bail 136, so that each time a shutter 70 is operated and moves bail 136 forward, shutter 155 moves forward also. It is assumed that the drum will have a longitudinal area provided with no perforations, except a single row under shutter 155 for the purpose of sending out a special signal, common to all characters, such as a start signal. When the drum has this longitudinal area perforated only for the start signal, it may be desirable to have the rows of perforations for character impulses followed, if required by the particular receiving mechanism, by a longitudinal strip in which would occur perforations only under shutter 155 for the purpose of transmitting a stop signal. It will be observed that this arrangement provides invariable and uniformly operating means common to all letters for the purpose of sending start and stop signals. With the arrangement just described, no variation in start and stop signals is possible and it is not subject to contact troubles common in transmitters wherein individual contact groups are operated for each character.

Operation

The operation of certain parts of the mechanism has been described above and it is thought that a brief description of the sequence of operation at this point will be sufficient to give a clear understanding of the operation of the transmitter.

Assume that the drum is rotating and the parts occupy the positions shown in Figures 1, 2 and 3 of the drawings. When a key 53 is depressed, the part 66 thereof engages bail 92 pressing it down and rotating bars 90 on shaft 50. Tooth 115 of the key engages edge 116 of locking bail 117 rotating the same in its supports against tension of spring 119. When tooth 115 passes below edge 116, the locking bail springs back locking down the key bar. Due to ball mechanism 111, it is impossible to depress two keys at once. The downward movement of the key causes spring pressed pawl 62 to engage the edge of member 56 tending to rotate it toward the right, as viewed in Fig. 1, against tension of spring 61. The member is restrained from moving for the time, since its arm 57 engages a shutter 70 which is locked against movement to the right by the engagement of the nose 148 of pawl 145 carried thereby against edge 149 of bail 36 (Fig. 5), but spring 65 and pawl 62 continue to exert pressure on arm 58 of member 56 tending to move the shutter toward the right.

Assume that the key was depressed when cam 20 was not under roller 25. In this case bail 36 is in its lower position and no upward pressure is exerted by the end of lever 45 on hook 46, so that the rotation previously referred to of bar 90 due to the downward movement of the key which also pulls down rod 96 turning triangle-shaped member 100 on shaft 101, and spring 104 connected between members 101 and 103 causes member 103 pinned to shaft 101 to rotate the latter, as well as hook 46 secured thereto, moving the end of the hook clear of arm 45 which like bail 36 is pinned to shaft 35.

When cam 20 passes under roller 25, bails 30 and 36 are raised, as previously described, releasing shutter 70 which moves toward the right under the tension of key pawl spring 65, uncovering the hole 75 in the shutter guide and per-

mitting a beam of light from lamp 80 to shine therethrough.

As cam 20 passes out of engagement with roller 25, bails 30 and 36 are lowered by spring 28, and edge 150 of bail 30 rests to the left of stop 151, Fig. 5, on selected shutter 70, holding the latter to the right until the next operation of the bails.

In moving toward the right under pressure from the shutter, bail 136, by means of the projection 138 on one of its arms 135, carries arm 125 toward the right so that the end thereof is positioned under depending member 124 on reset arm 121 which is oscillated every revolution by cam 21.

Cam 21 is so positioned in respect to cam 20 that the former is effective to engage its roller immediately after cam 20 has passed from under roller 25.

When cam 21 rotates arm 121, member 124 engages the end of arm 125 pressing down the latter as well as its supporting shaft 126, rotating the framework comprising arms 128 on shaft 129. This movement of arms 128 elevates the ends of spring connected levers 130, turning by means of cams 139 and 140 the locking bail 117 in counterclockwise direction, thus releasing the key held thereby and freeing the keyboard so that another key may be depressed. Bars 90, released by the unlatching of the key, are restored by spring 94 to their normal position and rod 96 frees hook 46 which is rotated to the left over arm 45 by spring 48 before the completion of the transmission of the character selected by the still operated shutter. The release of the key removes tension of spring 65 exerted through pawl 62 on member 56, and thereafter spring 61 exerts pressure on shutter 70 through arm 57 tending to move the shutter to the left, but the shutter is prevented from returning to unselected position for the time being by the engagement of projection 151 thereon with the right hand surface of depending edge 150 attached to bail 30.

If a key is depressed before the transmission of a character has been completed, after the keyboard has been released and while the cams 20 and 21 are ineffective, the parts operate in the manner described above, hook 46 being moved out of the path of arm 45, whereby on completion of the transmission of a character, the transmission of the next follows without interruption, the elevation of bails 30 and 36 permitting spring 61 to restore the shutter bar of the completed character to the left and also the movement to the right of the spring tensioned shutter connected to the last depressed key, as previously described.

If a key is depressed while arm 45 is under hook 46 and while roller 25 is on cam 20, the hook is kept in engagement with arm 45 by projections 107 and 108 on the hook and arm respectively, as previously described, which prevents these parts from disengaging and thus start the transmission of a letter at a critical part of the cycle. The key bar, however, will be locked down and transmission will proceed in the usual manner at the beginning of the next cycle.

In order to insure the restoration of a selected shutter at the end of a cycle, each shutter is provided with the latch arrangement previously described. The left side of nose 148 of latch 145 has a slanting surface which permits at the proper time in the cycle the shutter to pass to the left under edge 148 of bail 36 due to pressure of spring 61, irrespective of whether the bail is held down by hook 46 or not.

An arrangement for holding locking ball 117 against rotation when already holding down a key lever has been provided which consists of an arm 160 secured to the locking ball assembly, provided with a stud 161 over which fits a hook 162 formed in rod 163 connected to a stud 164 in the forward corner of the base of triangular shaped member 103. When hook 46 is turned toward the right by depression of a key and arm 45 rises in front of the hook, no movement of locking ball 117 is possible during this part of the cycle because a pull on rod 163 will cause the nose of hook 46 to strike the end of arm 45.

In a preferred embodiment of the invention, the perforations in the drum are arranged to modulate the light beam for character impulses and a start impulse.

Frequencies may be chosen that are suitable for transmission over transmission bands of the narrowest type, eliminating the difficulty of amplifying and transmitting former low frequency printer signals over high frequency communication lines. In one embodiment of a radio printing telegraph according to the present invention, the perforations in the drum for the start signal are arranged so that the light beam is modulated by a series of equidistant holes for each signal, the start signal being of a different frequency from those forming the character impulses. It is desirable and also possible without any extra complication, to use two different frequencies for starting signals and character impulses. Stop signals, if required, may be provided also. The use of a special frequency for a start signal makes it possible to characterize the start signals, not only by their length but also by their frequency. In consequence, the receiving printer synchronizing channel is completely separated from the signalling channel and this avoids any tendency of the synchronizing mechanism of being affected by the signalling impulses. Furthermore, the arrangement makes possible the use of separate filters for the start frequency by which disturbances which might cause false starts are filtered out. A preferred arrangement, for example, is to use a 540 cycle frequency for a start signal and one of 800 cycles for the character impulses.

With this arrangement the walls of the rotary drum are perforated with as many rings or circumferential rows of holes as there are characters to be transmitted. The number and grouping of any one ring is such that the beam of light directed at them from the outside of the drum falling on the photo-electric cell would be modulated at 540 cycles for a short interval, say 30 milliseconds for a start signal, and thereafter in a series of impulses of 800 cycles to represent the characters.

The perforations may be grouped to transmit facsimiles of the characters selected. Such a system is now about to be described.

The method used in this embodiment of a printing telegraph is to arrange the perforations in the drum to transmit for each letter or figure by seven horizontal lines, this number being selected to give a fair degree of detail when the character is recorded. With a line signal of this kind, the number of signals for each letter is consequently much higher than in the Morse or five unit code.

Transmitters have been designed in which the code for each letter or figure is transmitted by a contact operated at high speed by a cam. In this case the maintenance of these numerous cams and high speed contacts is an important

item, and the disadvantages with such former arrangements are overcome in the present invention where the code for each letter or figure is obtained by operating a small shutter which lets a beam of light through one row of perforations.

Figure 15 shows diagrammatically the impulse groupings for the characters "E," "2," and "N" in an arrangement where each character is divided into seven horizontal bands, impulses of the required length being transmitted in proper relative position for each band and the bands transmitted in succession for the purpose of operating a printer having means for recording the impulses successively to form a built-up character.

Figure 14 shows schematically a circuit by which the transmitter may operate a radio transmitter.

A photo-electric cell 87 has its anode connected to positive potential and its cathode through a resistance to ground. The cathode is connected to a grid of triode 200, the plate of the latter being connected through resistance 201 to positive potential. The plate is also connected through condenser 202 to the control grid of pentode 203. The pentode drives through transformer 204 a pair of tubes 205 working in push pull. Transformer 206 is in the output circuit from tubes 205 and a potentiometer 207 controls the output level.

The circuit operates as follows. The passage of each hole in the perforated cylinder below an open shutter produces an impulse in the photo-electric cell circuit and a difference in potential appears in the high resistance 199 connected between ground and the cathode of tube 200. The current is amplified by the triode and the difference of potential appears at the terminals of resistor 201, but is weak, owing to the tube's impedance.

The second tube 203 amplifies the signal and is coupled to tubes 205 through transformer 204 in push pull relationship. According to well known practice, the amplitude of variation in potential of the grids of tubes 205 is such that the plate current reaches saturation value for positive impulses, so that the output signals are independent of tube power or photo-electric cell sensitivity or ageing of the cathodes.

Fig. 11 shows schematically the connection of the transmitter just described to a radio transmitter, while Figure 12 shows diagrammatically a radio receiver and amplifier connected to a facsimile printer of the built-up letter type suitable for operation with the transmitter.

The printer comprises a motor 220 provided with known means, not shown, for maintaining a constant rate of speed sufficiently close to that of the transmitter to permit start stop operation. In the present arrangement about to be described, speed variation within reasonable limits does not cause the printing of a wrong letter but the letters are printed slanting in one direction or the other, the direction of the slant indicating whether the speed is high or low, and the degree of slant, the speed difference. Consequently, speed adjustments are easily maintained.

Motor shaft 221 is connected to a second shaft 222 by clutch 223 consisting of a pawl 224 and ratchet 225, fixed respectively on shafts 222 and 221. Pawl arm 226 cooperates with armature 227 of start magnet 228, one terminal of which is connected to ground and the other to the front contact 229 of relay 220 which has an armature 231 connected to a grounded source of potential.

A cam 232 on shaft 222 engages a roller 233 at the end of arm 234 pivoted at 235. A link 236 connects arm 234 with chariot 237, Fig. 12, which reciprocates horizontally in suitable guideways under the influence of cam 232 and spring 238 connected to arm 234. In the present embodiment the chariot supports seven styli 240 which are vertically movable in apertures in the chariot against the tension of individual springs, not shown. A top view of the chariot is shown in Fig. 13.

A print hammer 241 is disposed above the chariot and a platen 242 over which passes an inked ribbon 243 and a paper tape 244. The printhead is mounted on an arm 245 pivoted at 246 and held normally against stop 247 by spring 248. The printhead is oscillated by magnets 250 and 251 secured between the pole-pieces 252 of a permanent magnet, the armature 253 thereof being connected to the printhead. The magnet and armature arrangement is similar to that of a balanced armature loud-speaker unit.

One terminal of magnets 250-251 is connected to the amplifier by circuit 255. The other is connected to contact 257, the tongue 258 therefore being connected via circuit 256 to the amplifier. Relay 230 has one terminal connected to the amplifier via circuit 255 and the other by contact 259, tongue 258 and circuit 256, only when the cam is in stop position, tongue 258 being moved away from contact 257 and into engagement with contact 259 by an insulating pin 260 carried by cam 232 which engages the tongue just as the cam reaches stop position, as shown in the drawings.

The printer operates as follows. Assuming the printer and transmitter motors are running at the proper relative speeds and that the transmitter key has been depressed for the letter "E" sending out a series of spaced impulses commencing with the 540 cycle start signal, as shown in Figure 15.

On receipt of the start signal which passes through an appropriate filter and amplifier indicated by the block diagram of Fig. 12, relay 230 is momentarily energized and operates start magnet 238 by a circuit from its tongue through the windings of the start magnet to ground. The operation of the start magnet withdraws its armature 227 out of the path of the arm 226 of pawl 224, and the pawl in response to pressure from a spring, not shown, engages the teeth of ratchet 225 causing shaft 222 and cam 232 to rotate.

The rotation of the cam carries arm 234 and chariot 237 toward the right of the drawing, the cam being so synchronized with the transmitter drum that the stylus 240 for the first band traverses a distance over the platen while under the printhead equal to the width of a letter while the first band is being transmitted, and then passes beyond the printhead. The first band is followed by the second band. During reception of the second band the stylus moves under the hammer so that on operation thereof it contacts the paper tape making a mark adjacent to and below the path of the first stylus, and so on, for the remainder of the stylus.

As the printing of a letter progresses, cam 232 moves arm 234 further to the right until the seventh and last stylus has completed its travel under the printhead. Shortly thereafter the high part of the cam passes from under roller 233 and the arm is snapped back to the left by spring 238.

A tape feed mechanism is operated by a pawl 265 connected by a pivot 267 to an arm 268 supported on a pivot 269 and also connected to a link 265a connected at its other end to arm 234 by pivot 266. During the movement of arm 234 to the right, the pawl drops behind a tooth in a ratchet wheel 270 provided with a detent, not shown, secured to a roller which cooperates with a pressure roller 271 to feed paper tape 244. The reverse movement of arm 234 toward the left causes the pawl to turn the ratchet and advance the tape a distance of one letter space. Suitable means, not shown, are used for feeding the ribbon 243.

On the completion of the reception of a letter, cam 232 carries insulating pin 260 into engagement with contact tongue 258, breaking the circuit to magnets 250 and 254 and connecting the amplifier via contact 259 again to start relay 230 to await reception of the next start impulse.

Pawl arm 226 of the clutch strikes armature 227 disconnecting the pawl from the ratchet 225 and stops rotation of the cam until reception of the next start pulse.

The movement of the styli is very sensitive and the printhead follows the signalling currents accurately, the characters being printed to conform to the perforations in the transmitter drum. In a printer of the kind described, the only non-printing function required is the word space and the space bar of the transmitter when operated merely causes the transmission of a start signal causing the receiver to start and stop in the manner above described, and since no impulses are transmitted to actuate the printhead the unmarked tape is advanced the distance of a word space.

While the present invention has been disclosed with reference to specific embodiments thereof, it will be understood that these embodiments are merely presented by way of example and that many modifications of the invention will be suggested thereby to those skilled in the art without departing from the spirit or scope of the invention.

45. What is claimed is:

1. A transmitter for telegraph signals comprising a source of light, a photo-electric cell controlled by said source, an external transmission circuit controlled from said photo-electric cell, means for selectively controlling said photo-electric cell for transmitting impulses comprising a rotary drum having the surface thereof disposed between said source and said photo-electric cell, a plurality of perforations in said drum arranged in groups, means normally tending to prevent rays of light from said source from striking said photo-electric cell through said perforations, a keyboard for operating the last mentioned means to permit rays of light to pass through a group of perforations corresponding to the key depressed whereby impulses corresponding to said group of perforations are sent to the transmission circuit, and means independent of said last mentioned means for transmitting an invariable start signal on the operation of each key.

2. A transmitter for telegraph signals comprising a source of light, a photo-electric cell controlled by said source, an external transmission circuit controlled from said photo-electric cell, means for selectively controlling said photo-electric cell for transmitting impulses comprising a rotary drum having the surface thereof disposed between said source and said photo-electric cell, a plurality of perforations in said drum arranged

in groups, means normally tending to prevent rays of light from said source from striking said photo-electric cell through said perforations, a keyboard for operating the last mentioned means to permit rays of light to pass through a group of perforations corresponding to the key depressed whereby impulses corresponding to said group of perforations are sent to the transmission circuit, and means to transmit a uniform start signal for each character transmitted, comprising a group of perforations in said drum, means normally tending to prevent rays of light from said source from striking said photo-electric cell through said start signal perforations and means for operating the last-mentioned means to permit rays of light to pass through said start signal perforations, actuated by the operation of said ray-preventing means.

3. In a transmitter for telegraph signals the combination of a source of light, a photo-electric cell, a rotary drum disposed between said source and said photo-electric cell having a plurality of rows of perforations, the perforations in each row being arranged in groups according to code combinations of impulses and spaced a predetermined distance from each other to interrupt the light from said source at a predetermined frequency, shutter means comprising a shutter individual to each row of perforations normally excluding light from passing through said perforations to said photo-electric cell, and perforations in said drum differently spaced from the above mentioned perforations and disposed to modulate light from said source to provide a start signal before the transmission of each code combination and at a different frequency therefrom.

4. In a printing telegraph transmitter, a rotary drum, a plurality of groups of perforations in the surface of said drum, photo-electric means and a light source cooperating with the perforations of said drum, shutter means comprising a shutter member individual to each group of perforations, a keyboard having keys, means actuated by the keys for selectively moving the respective shutter members from a normal position to an operated position, and means for resetting an operated key to normal position, and a detent arranged to hold the shutter member controlled thereby in operated position after said key has been reset.

5. In a printing telegraph transmitter, a rotary drum, a plurality of groups of perforations in the surface of said drum, photo-electric means and a light source cooperating with the perforations of said drum, shutter means comprising a shutter member individual to each group of perforations, a keyboard having keys, key-actuated means for selectively moving the respective shutter members from a normal position to an operated position, key detent mechanism for retaining an operated key in operated position, a key lock-out device actuated by the operation of any key to lock all other keys out of operation, a key reset mechanism, and a detent arranged to hold a shutter member in operated position after the key which actuates said shutter has been reset, the arrangement being such that a second key may be operated while the shutter operated by the reset key is still in operated position.

6. In a printing telegraph transmitter, a rotary drum, a plurality of groups of perforations in the surface of said drum, photo-electric means and a light source cooperating with the perforations of said drum, shutter means comprising a shutter member individual to each group of per-

forations, a keyboard having keys for selectively moving the respective shutter members from a normal position to an operated position, and means effective at a predetermined point in the rotary cycle of the drum to permit restoration of a selected shutter from operated position to normal position, key detent mechanism for retaining an operated key in operated position, a key lockout device actuated by the operation of any key to lock all other keys out of operation, a key reset mechanism, and a detent arranged to hold a shutter member in operated position after the key which actuates said shutter has been reset, the arrangement being such that a second key may be operated while the shutter operated by the reset key is still in operated position.

7. In a facsimile transmitter a drum, a plurality of circumferential rows of perforations in said drum, the perforations in each row being so arranged as to correspond to the impulses required in transmitting a character, photo-electric circuit means controlled by said perforations for producing impulses corresponding to said perforations, and means to transmit a start pulse for each character comprising a separate row of perforations, start signal photoelectric circuit means and means for automatically energizing said latter means in advance of the generation of said impulses controlled by any of said rows of perforations.

8. In a facsimile transmitter, a drum, a plurality of circumferential rows of perforations in said drum, the perforations in each row being so arranged as to correspond to the impulses required in transmitting a character, photo-electric circuit means controlled by said perforations for producing impulses corresponding to said perforations, perforations in said drum effective to control said photo-electric circuit means in advance of those perforations corresponding to characters for sending out a start signal, and means for selectively energizing the photoelectric circuit means through said former perforations to transmit a character and automatically energizing said photoelectric circuit means through the latter perforations in advance.

9. A transmitter for telegraph signals comprising a rotary drum having a plurality of perforations arranged in axially spaced circumferential signal groups, a source of light on one side of the perforated drum surface, a photoelectric cell on the opposite side of said surface arranged to receive through said perforations rays of light from said source, a plurality of shutters each normally arranged to intercept rays from said source passing through a group of perforations, means for selectively opening the shutters including keys arranged in a keyboard, means for locking the shutters against movement during a signal cycle of rotation of the drum and releasing the shutters between cycles, and means for actuating said opening means by key operation during said signal cycle, effective at the end of said cycle.

10. A transmitter as set forth in claim 9, in which the shutter opening actuating means includes a shutter shifting device, an associated key, means for locking the key in actuating position, and a spring connection between the key and said device yieldable to permit movement of the key to actuating position while a shutter associated with said device is locked in position, operative upon unlocking of said shutter to actuate said device and thereby shift the shutter into open position.

11. A transmitter for telegraph signals com-

prising a rotary signal member including a plurality of axially spaced signal generating elements, a plurality of associated actuating members mounted adjacent the rotary member and means for selectively shifting the actuating members into and out of signal generating position including a member shifting device and a movable key associated with each operating member, a yieldable drive connection between said key and device arranged to actuate the device when the key is depressed, a locking device for retaining the member in operating position and a reset mechanism for returning the key to normal position while said operating member and device are in signal generating position.

12. A transmitter as set forth in claim 11, including a locking device for holding operating members in position during a signal generating cycle of rotation of said rotary device, said yieldable connection being arranged to yield upon depression of the associated key while the associated member is locked in position and operative to actuate said device and shift the member when the locking device is released at the end of a signal cycle.

13. A transmitter for telegraph signals comprising a rotary signal generating member, including a plurality of axially spaced signal generating elements, a plurality of operating members each associated with one of said elements, means including a key associated with each operating member for shifting said member into and out of signal generating position, means for locking said operating members during a signal generating cycle of rotation of said rotating member and unlocking said operating members between successive cycles, and locking means for preventing key actuation of said operating members while said first mentioned locking means is in unlocked position.

14. A transmitter as set forth in claim 13, including a key locking device arranged to retain a key in operated position, a key reset device for releasing the locking device to return the locked key to normal position, and a detent device for holding the resetting device against operation, and means for actuating said detent device when said member locking device is in unlocked position.

15. A transmitter for telegraph signal comprising a rotary signal generating member, including a plurality of axially spaced signal generating elements, a plurality of operating members each associated with one of said elements, a control signal generating element carried by the rotary device, an operating member associated therewith, means for selectively actuating the signal operating members and means actuated by the operation of any signal operating member for actuating the control signal operating member.

16. A transmitter for telegraph signals comprising a rotary signal generating member including a plurality of axially spaced signal elements, a plurality of operating members each associated with a signal element and movable into and out of engagement with said element along a predetermined path, a signal control element carried by the rotating member, an associated operating member, means for selectively shifting said first mentioned operating member into and out of operative position along said path, and means for actuating said last named operating member when any one of the other members is actuated, comprising a shifting member extending across said path and shifted by the move-

ment of any operating member along the path.

17. A transmitter as set forth in claim 13, including a key reset construction placed in an operative condition by said shifting member.

18. A printing telegraph system comprising a transmitter including means for sending a control signal at a predetermined frequency and means for sending character signals at a different frequency, and a receiver including a printing mechanism, control means for starting and stopping said mechanism, a signal receiving system including a circuit tuned to the control signal frequency, means operated by a signal impulse in said circuit for actuating the control means, a

19. A printing telegraph system as set forth in claim 18, in which the sending means includes a rotating member, axially spaced groups of signal impulse generating elements circumferentially spaced on the member at multiples of a uniform interval, an axially spaced circumferential group of control signal generating elements spaced at multiples of a different interval, stationary means associated with each of said groups for generating signal impulses synchronous with the passage of each of said signal impulses from all of said groups.

20. A printing telegraph system as set forth in claim 18, in which the means operated by a signal impulse includes a clutch mechanism and an electromagnet controlling the clutch mechanism, and in which the means controlled by impulses in the second circuit includes an electromagnet energized during each of said impulses, and means actuated by said latter magnet when energized for placing said mechanism in printing position.

21. A printing telegraph system as set forth in claim 18, in which the sending means includes a rotating drum, a plurality of axially spaced circumferential groups of message signal perforations through said drum, an axially spaced group of control signal perforations through said drum, the perforations of each message signal group being spaced by multiples of the same interval and the perforations of the control signal group being spaced by multiples of a different interval, a photoelectric cell on one side of the drum surface and a source of light at the opposite side of said surface, arranged to project light rays through said perforations onto the photoelectric cell when said perforations pass through a signal generating station, a shutter for each of said groups of perforations, means for selectively opening the message signal shutters, means for opening the control signal shutter whenever a message signal shutter is opened, means for transmitting impulses from a photoelectric cell, means for receiving said impulses, message printing mechanism, means tuned to the control signal frequency for controlling the starting and stopping of said mechanism, and means tuned to the message signal frequency for actuating the mechanism to print a message.

22. A cyclically operating telegraph transmitter having means for selectively transmitting a plurality of signal characters, one for each cycle of operation, comprising a plurality of signal operating members, a plurality of keys, one for each signal operating member, means operative when a key is depressed to lock said key in depressed

position for a period of time ending a predetermined time after the beginning of the next succeeding cycle of operation, means to limit the time during which said signal operating members may be moved into or out of operating position to a small predetermined portion of said cycle of operation, and energy storing means operatively connecting each key with its associated signal operating member, whereby a key may be depressed at any part of said cycle of operation and said associated operating member will operate during said predetermined portion of said cycle of operation.

23. A transmitter as set forth in claim 22, including means to permit the operation of only one key at a time.

24. A transmitter as set forth in claim 22, including positive means to reset a depressed key at the end of the locking period.

25. A transmitter as set forth in claim 9 in which the shutter opening actuating means includes a shutter shifting device, an associated key, means for locking the key in actuating position, and a connection between the key and said device biased for operation of said device by depression of the key while a shutter associated with said device is locked in position, effective upon unlocking of said shutter to actuate said device and thereby shift the shutter into open position.

26. A transmitter for telegraph signals comprising a rotary signal member including a plurality of axially spaced signal generating elements, a plurality of associated actuating members mounted adjacent the rotary member and means for selectively shifting the actuating members into and out of signal generating position including a member shifting device and a movable key associated with each operating member, a drive connection between said key and device biased by depression of the key for actuation of the device, a locking device for retaining the member in operating position and a reset mechanism for returning the key to normal position while said operating member and device are in signal generating position.

27. A cyclically operating telegraph transmitter having means for selectively transmitting a plurality of signal characters, one for each cycle of operation, comprising a plurality of signal operating members, a plurality of keys, one for each signal operating member, means operative when a key is depressed to lock said key in depressed position for a period of time ending a predetermined time after the beginning of the next succeeding cycle of operation, means to limit the time during which said signal operating member may be moved into or out of operating position to a small predetermined portion of said cycle of operation, and means operatively connecting each key with its associated signal operating member biased by depression of a key at any part of said cycle of operation for operation of such member during said predetermined portion of said cycle of operation.
28. A transmitter as set forth in claim 22 in which the means to limit the time for movement of the signal operating members to a small predetermined portion of each cycle of operation comprises means for locking any operated signal operating member in operating position for substantially a cycle of operation and then unlocking such operated signal member at the beginning of the next succeeding cycle for a short period of time terminating before the unlocking of a key depressed in the preceding cycle.
29. A transmitter as set forth in claim 22 in which the means to limit the time for movement of the signal operating members to a small predetermined portion of each cycle of operation comprises means for locking all unoperated signal operating members in position, unlocking means rendered effective at the beginning of a cycle of operation to exert a stress on such locking means to unlock said unoperated signal operating members, and means rendered effective by depression of a key during the unlocking period to determine the next signal operating member to be moved to operating position and to prevent unlocking of the unoperated signal operating members until the end of the cycle.

EDMOND MAURICE DELORAINNE.
